UNITED STATES PATENT OFFICE.

CHARLES G. TAYLOR, OF HARTFORD, CONNECTICUT.

COMBINED KEY-RING, TAG, CIGAR-CUTTER, AND SCREW-DRIVER.

No. 834,334.

Specification of Letters Patent.

Patented Oct. 30, 1906.

Application filed October 2, 1905. Serial No. 281,071.

To all whom it may concern:

Be it known that I, CHARLES G. TAYLOR, a citizen of the United States, residing at Hartford, in the county of Hartford and State of Connecticut, have invented certain new and useful Improvements in Cigar-Cutters, of which the following is a specification.

This invention relates to a combined implement for use as a tag for a key-ring, a cigar-clipper, and a screw-driver.

In the accompanying drawing the figure is a side view of the improved implement.

Referring to the drawing, the numeral 5 designates a key-ring of any approved type; 2, a tag perforated at 3 at one end to receive said key-ring and at 4 at its opposite extremity, the perforation 4 being countersunk at 4' more readily to receive a cigar-tip.

20 Connected to the back of the tag by a pivot 6' is a blade 6, shaped to form a screw-driver 7 at one end and sharpened on its lower edge at 8 to form the movable knife 9 of a cigar-clipper.

25 As will be observed from the drawing, the lower end of plate 6 is curved at 9² to conform to the curved lower surface of the tag 2 when said blade is turned upon its pivot to rest parallel with the longitudinal axis of said tag.

30 By pivoting the blade adjacent to the edge of the tag, as shown at 6', a broad bearing-surface is formed for said blade against the tag when it is swung at right angles thereto, thereby affording sufficient support for the rounded end of the blade above its pivot to be sustained against deflection when the device is used as a screw-driver.

35 In the drawing the blade 6 is shown swung on its pivot to a partially open position, the screw-driver end of the same constituting a handle by which the blade may be manipulated to clip off the tip of a cigar; but to prevent interference with the pocket the blade 45 may be swung inward so that it will be in line with and will be concealed by the body of the tag.

When the screw-driver 7 is to be used, the blade is swung downward on its pivot until

said end 7 lies in a vertical plane, when the 50 tag will serve as a handle for turning the screw-driver.

As will be observed, the pivot 6' is located contiguous to the inner edges of the tag 2 and blade 6, thereby enabling the cutting edge 8 to be operated with the greatest amount of leverage. Furthermore, by so locating the pivot the body of the blade is readily brought back of the tag, and when used as a screw-driver the blade finds a ready support against 60 the rear wall of said tag and is prevented from deflection while actuating the screw.

I am made aware that it is not new to have a cigar-cutter in which the cutting-blade is pivoted upon another blade in which is the 65 perforation for the cigar-tip; but in such construction the cutting-blade is pivoted along the middle line of the other blade and has its cutting end sharpened upon both sides with a point, thus forming an eraser.

In my device the cutting-blade is pivoted off from the middle line of the perforated tag and adjacent to the edge of the tag and has one cutting edge only on the side of its pivot.

70 With such construction as described there is produced a cigar-cutter with which danger of the cutting edges of the cutting blade being moved to one side and catching into anything, such as the interior of a 80 pocket, is obviated, as there is not any point to catch, and on one side the end of the cutting-blade is blunt and could not catch, and though the other side has a cutting edge there is not a point to be pushed in, and any 85 pressure against that edge would rather tend to swing the blade into alinement with the other blade than to cause it to cut.

Having thus described the invention, what I claim is—

As an article of manufacture an implement consisting of an oblong tag provided with a curved lower end perforated to receive a cigar-tip, and a plate shaped to tool form at its outer end, and having one extremity 95 curved and opposite the curve an inclined cutting edge, said plate being pivoted adjacent to its edge near the edge of the tag,

2
and being of substantially the length of the tag, whereby a long leverage is obtained, and when the plate is turned on its pivot to a position parallel with the tag the cutting edge will be concealed behind said tag, and the curved surfaces of the plate and tag will be concentric, and when the plate is turned at right angles to the tag a bearing-support of the width of said tag is provided to resist

torsional strain when the tool at the end of 10 said plate is in use.

In testimony whereof I affix my signature in presence of two witnesses.

CHARLES G. TAYLOR.
